COMBINED WATCH CASE AND WATCH BAND

Paul G. Nolin, Cohoes, N. Y.

Application February 13, 1953, Serial No. 23,605

Term of patent 7 years

(CL. D45—4)

To all whom it may concern:

Be it known that I, Paul G. Nolin, a citizen of the United States, residing at Cohoes, in the county of Albany and State of New York, have invented a new, original, and ornamental Design for a Combined Watch Case and Watch Band, of which the following is a specification, reference being had to the accompanying drawing, forming a part hereof.

Figure 1 is a perspective view of a combined watch case and watch band, showing my new design;

Figure 2 is a side elevational view thereof with the watch band in a slightly different position; and

Figure 3 is a top plan view thereof as shown in Figure 2.

The dominant feature of my design resides in

the portions shown in full lines, the dotted line showing at the strap ends represents stitching.

I claim:

The ornamental design for a combined watch case and watch band, as shown and described.

PAUL G. NOLIN.
